his Attorneys.

UNITED STATES PATENT OFFICE.

JAMES H. RAND, OF NORTH TONAWANDA, NEW YORK.

INDEX.

1,286,406.

Specification of Letters Patent.

Patented Dec. 3, 1918.

Application filed April 20, 1918. Serial No. 229,674.

To all whom it may concern:

Be it known that I, JAMES H. RAND, a citizen of the United States of America, and resident of North Tonawanda, in the county of Niagara and State of New York, have invented new and useful Improvements in Indexes, of which the following is a specification.

This invention relates to index devices 10 and consists in the novel and improved features hereinafter described and particularly pointed out in the claims.

In the accompanying drawings which illustrate the invention,—

15 Figure 1 is a vertical cross section, partly in elevation, of an embodiment of the invention;

20 Fig. 2 is a vertical longitudinal section of part of an index device containing the invention on line 2—2 of Fig. 1;

Fig. 3 is a section on an enlarged scale of one of the composite index elements on line 3—3 of Fig. 1;

25 Fig. 4 is a fragmentary section on a still larger scale of one of the index elements on line 4—4 of Fig. 1;

Fig. 5 is a perspective view of one of the card holders;

30 Fig. 6 is a perspective view of one of the cards; and

Fig. 7 is a perspective view of a sheet 35 hereinafter described.

The frame by which the index elements are held consists preferably of a box or tray 40 1, having oppositely disposed channels 2, 2, near its bottom.

A series of transverse wire rods 3 extend between the channels 2, 2, with their ends loosely held therein so that they may slide 45 lengthwise of the channels.

50 A series of upstanding, composite index elements are attached to the rods 3, and swing on the rods as hinge members. Each index element, as herein shown, comprises a 45 card holder 4, preferably of transparent sheet celluloid, having a fold or bent-over member 5 at its bottom edge through which the rod 3 extends, and a folded lip 6, constituting card engaging means at the top. A card 7 is held at its upper edge by the card 55 engaging lip 6 and is of substantially the same height as the card holder 4, so that its bottom edge which is wholly unattached to the card holder, may rest upon the bottom of the tray 1, which prevents the top edge of the card from slipping out from under the

lip 6 and becoming disengaged therefrom. The tray bottom constitutes stationary means, common to all of the cards in the series, to prevent the disengagement of the 60 tops of all the cards from their card engaging lips.

Each card may be provided with an index tab 8 projecting from its upper edge, and the fold of lip 6 is in that event provided with 65 a slot or aperture 9 through which the tab projects; the tabs and the corresponding slots of the several index elements may be arranged in rows from front to rear, or in diagonal or "stepped" positions, or otherwise 70 as desired. The tabs may also be of any usual or desired construction, those herein shown being formed of a folded piece of transparent sheet celluloid cemented to the margin of the card, forming a sheath or 75 pocket into which a slip may be inserted bearing the desired index characters.

The matter to be recorded in the index may be inscribed upon the cards 7, which being readily removable, may be replaced 80 as often as necessary. Or, if the nature of the records involves a too rapid using up of space or a too frequent discarding or changing of the records, a saving can be effected by retaining the cards 7 as a permanent part 85 of the equipment, and entering the records on sheets of paper 10 folded over the top edge of the card, and provided with a slit 11 through which the tab 8 projects.

I claim:

1. An index device comprising a tray, and a series of movable, upstanding composite index elements each comprising a card holder of sheet material having a card engaging means at its top edge, and a card whose top edge is held by said card engaging means, the bottom of the tray cooperating with the bottom edge of the card to prevent disengagement of the card from the card engaging means.

2. An index device comprising a tray, and a series of movable, upstanding composite index elements each comprising a card holder of sheet material having a card engaging lip at its top edge, and a card whose top edge is held by said card engaging lip, the bottom of the tray cooperating with the bottom edge of the card to prevent disengagement of the card from the card engaging lip.

3. An index device comprising a tray, and a series of movable, upstanding, composite index elements each comprising a card

holder of sheet material having card engaging means at its top edge, and a card whose top edge is held by said card engaging means, the bottom of the card being wholly unattached to the card holder, and stationary means common to all of the elements adapted to engage the bottom edges of the cards to prevent disengagement of the tops of the cards from their respective card engaging means.

4. An index device comprising a tray having oppositely disposed channels near the bottom, a series of transverse rods whose ends are loosely held in said channels whereby they may slide lengthwise of the channels, and a series of upstanding, composite index elements, each comprising a card holder of sheet material attached at the bottom edge to one of the rods and adapted to swing thereon, and having card engaging means at its top edge, and a card whose top edge is held by said card engaging means, the bottom of the tray cooperating with the bottom edge of the card to prevent disengagement of the card from the card engaging means.

5. An index device comprising a tray having oppositely disposed channels near the bottom, a series of transverse rods whose ends are loosely held in said channels whereby they may slide lengthwise of the channels, and a series of upstanding, composite index

elements, each comprising a card holder of sheet material having a folded member at the lower edge engaging one of the rods and being adapted to swing thereon, and having a card engaging lip at its top edge, and a card whose top edge is held by said card engaging lip, the bottom of the tray co-operating with the bottom edge of the card to prevent disengagement of the card from the card engaging lip.

6. A composite index element comprising a card holder of sheet material, having a folded card engaging lip at one edge, the fold of said lip having an aperture therein, and a card whose edge is held by said card engaging lip, the card having an index tab projecting through said aperture in the fold of the lip.

7. A composite index element comprising a card holder of sheet material having a folded card engaging lip at one edge, the fold of said lip having an aperture therein, and a card whose edge is held by said card engaging lip, the card having an index tab projecting through said aperture in the fold of the lip, and a sheet folded over the edge of the card which is held by the lip, and having a slit through which the tab extends.

Signed by me at Boston, Massachusetts, this twelfth day of April, 1918.

JAMES H. RAND.
